[57] CLAIM

The ornamental design for flexible cat exerciser, as shown.

DESCRIPTION

FIG. 1 is a perspective view of a flexible cat exerciser showing my new design;

FIG. 2 is another perspective view thereof showing the exerciser in a flexed position; and

FIG. 3 is a cross sectional view thereof taken on line 3-3 of FIG. 1.

FIG. 1

FIG. 3

U.S. Patent

Dec. 6, 1988

Sheet 2 of 2
